(57) **CLAIM**

The ornamental design for a mobile electrical oil radiator, as shown and described.

DESCRIPTION

FIG. 1 is a perspective view of the mobile electrical oil radiator;

FIG. 2 is a front view of the mobile electrical oil radiator;

FIG. 3 is a rear view of the mobile electrical oil radiator;

FIG. 4 is a left side view of the mobile electrical oil radiator;

FIG. 5 is a right side view of the mobile electrical oil radiator;

FIG. 6 is a top view of the mobile electrical oil radiator; and,

FIG. 7 is a bottom view of the mobile electrical oil radiator.
